US00D785793S

(12) **United States Design Patent** (10) Patent No.: **US D785,793 S**
Landanger (45) Date of Patent: **** May 2, 2017**

(54) **DEVICE FOR MITRAL PROSTHESIS ROPE LAYING**

(71) Applicant: **LANDANGER**, Chaumont (FR)

(72) Inventor: **Benoît Landanger**, Ruffey les Echirey (FR)

(73) Assignee: **LANDANGER**, Chaumont (FR)

(**) Term: **15 Years**

(21) Appl. No.: **29/567,943**

(22) Filed: **Jun. 14, 2016**

(51) LOC (10) Cl. **24-02**

(52) U.S. Cl.

USPC **D24/140; D24/133**

(57) **CLAIM**

The ornamental design for a device for mitral prosthesis rope laying, as shown and described.

DESCRIPTION

FIG. 1 is a rear perspective view of a device for mitral prosthesis rope laying;

FIG. 2 is a front perspective view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a front elevation view thereof; and,

FIG. 8 is a rear elevation view thereof.

The broken lines shown represent unclaimed subject matter and form no part of the claimed design.

1 Claim, 5 Drawing Sheets
